UNITED STATES PATENT OFFICE

GEORGE W. NICELY, OF MONTREAL, QUEBEC, CANADA, ASSIGNOR TO BRITISH AMERICAN SILK MILLS LIMITED, OF MONTREAL, CANADA

FEELER MOTION FOR AUTOMATIC SILK LOOMS

Application filed August 26, 1929, Serial No. 388,500, and in Canada July 24, 1929.

This invention relates to new and useful improvements in looms and particularly to looms of the automatic type and the object of the invention is to provide a feeler mechanism to indicate that the filling threads are nearly completed on an automatic silk loom, said mechanism being adapted to throw the automatic replenishing mechanism into play.

According to my invention, I provide a pair of feelers resiliently mounted in a suitable insulating block, adjustably secured to the loom. The feelers normally contact with the thread around the bobbin of material being woven. The bobbin has wound therearound at one end a layer of soft metal which underlies the thread. When the thread uncovers the metal, the feelers come into contact therewith and as these feelers are electrically connected to a solenoid which is connected to the replenishing mechanism, the current to said solenoid is completed and the replenishing mechanism is called into play to insert a full bobbin into the loom shuttle and discharge the empty one therefrom. This insertion of one bobbin and the removal of the empty one is obtained through the movement of the transerrer, and means are provided to pull the feelers clear of the shuttle while the change is taking place.

In the drawings which illustrate one form of my invention,

Figure 1 is a sectional longitudinal view of my improved bobbin.

Figure 2 is a side elevation of a shuttle with my improved bobbin mounted therein.

Figure 3 is a plan view of the shuttle, bobbin, picker stick and feeler motion, the connection between said mechanism and the replenishing solenoid being shown diagrammatically.

Figure 4 is an end view showing the feeler mechanism and part of the loom.

Figure 5 is a front view showing the relative position of the various elements pertinent to my improved feeler mechanism.

Referring more particularly to the drawings, 11 designates a bobbin of the usual type having a central bore 12. One end of the

bobbin is provided with rings 13 fitting into grooves 14 and these rings engage with grooves 15 formed in spring grips 16 secured to one end of the shuttle 17. The shuttle has a slot 18 formed therein adapted to register with a slot 19 formed in the guides 20. The shuttle while in operation moves during part of its operation back and forth on the breast beam 21 as indicated by arrows 22. Mounted in a slot in said guide is the picker stick 23 to which is attached the picker 24 adapted to receive and cushion the shock of the flying shuttle. Mounted on the machine is the solenoid 25 which is connected by suitable mechanism such as the rod 26 to contact with a lever 27 which when the solenoid is energized is pushed upwardly to contact with the actuator 28, which when held is adapted to operate through suitable mechanism (not shown) the transerrer 29. This transerrer is adapted to knock into place in the shuttle a filled bobbin, said filled bobbin displacing the empty bobbin in the shuttle. The shuttle moves back and forth as indicated by the arrows 22 before the shuttle is thrown towards the other side of the machine. The foregoing is descriptive of one type of automatic loom, all parts of which are old and well known in the art and the drawings is only shown diagrammatically to simplify the reading thereof. Only parts of the loom are shown which are controlled by the movement of the solenoid or parts which are necessary to pull the feelers clear of the bobbin while being changed.

My improvement lies in the feeler mechanism which is adapted to operate the solenoid.

In making my improvement, I first wrap around one end of the bobbin a layer 30 of tin foil or like soft metallic conducting material which is adapted to act as a bridge between the feelers hereinafter described. The thread is wrapped around the tin foil. My reason for using the tin foil is that point pressure may be exerted on the threads wrapped therearound without cutting the thread during the operation of the loom. Slidably mounted in a suitable insulating block 31, preferably wood, are the feelers

32 which consist of wires or rods, the ends of which project through the wooden block and on each side thereof. The feelers are insulated from one another and equipped 5 with nuts 34, which contact with the block to prevent the rod from being pushed therethrough. These rods are resiliently held by any suitable means against the threads on the bobbin as they pass through the slots in 10 the guide and in the shuttle. The preferred form of holding means shown in the drawings are in the form of flat springs 35, the free ends of which contact with the nuts. These springs may be slotted to allow free 15 movement of the rods. The springs also act as conductors and are connected to the current supply to the solenoid in such a manner that when the bridging element on the bobbin is exposed and makes contact with the 20 feeler rods, the circuit to the solenoid is closed, calling same into operation. The block is connected to a bracket 36 by bolts 37, said bracket being slotted to allow the block to be moved in the longitudinal direction 25 of the bobbin. The bracket is attached to the breast beam by any suitable means which will allow the bracket to be moved towards and away from the bobbin. In the drawings, the bracket is shown slotted and 30 screw bolts pass through the slots into the breast beam. This double adjustment allows the feelers to be carefully placed so that they will pass through the slots in the guide and the shuttle. The ends 33 of the feelers are 35 bent upwardly and passed loosely through openings formed in the ends of a bar 38 which is supported on the bent end of the feelers by means of the nuts 40 and constitutes a link connection which provides 40 for independent movement of the feelers so that they will both contact with the tin foil. This bar 38 is adapted to contact with an extension 39 of the doffing hammer, when 45 said hammer is in operation to discharge the bobbin.

In operation, the loom works in the usual manner, that is, the shuttle and guide move towards and away from the feelers between the flying movement of the shuttle. As the 50 thread on the bobbin gradually decreases and is woven into the material being manufactured, the tin foil becomes exposed. The tin foil when bare or substantially so, bridges the gap in the solenoid circuit between the feelers, thereby calling the operation of the solenoid into play. The solenoid moves upwardly and operates a link and lever which contacts with the actuator to hold same against motion. This pawl is 55 adapted to bring the replenishing mechanism, not shown, into play to force the transfferer down towards the shuttle and bobbin therein. The end of the hammer which does the changing carries with it a 60 full bobbin and forces same into the shuttle 65

thereby driving therefrom the empty bobbin. It will be seen that it is necessary to withdraw the feelers from the bobbin and preferably from the shuttle while the changing of bobbins is taking place and this is 70 accomplished by means of the transfferer extension which contacts with the bar joining the ends of the feelers as the transfferer is descending. The feelers are thus drawn out of the way of the changing bobbins and on the return of the transfferer the flat springs automatically return the 75 feelers to their operative position.

In the drawings, I have shown one form 80 of resilient means for holding the feelers in contact with the bobbin, but it will be readily understood that many modifications may be made thereto without departing from the spirit of the invention.

The device is very simple and positive in 85 its action and provides a delicately adjustable means for bringing the replenishing mechanism of a loom into play before the thread is completely unwound from the bobbin thereby preventing termination of the thread between the edges of the material being woven and necessitating stoppage of the machine to make the necessary connection in the weave.

Having thus described my invention, what 95 I claim is:

1. In a loom, a bobbin having a metallic 100 wrapping thereon, replenishing mechanism including a transfferer, an insulated block, feeler mechanism comprising a pair of spaced feeler elements slideable through said blocks, means for limiting the movements of said elements in one direction, resilient means urging and normally maintaining 105 said elements in contacting engagement with said bobbin, a bar connecting the corresponding outer extremities of said elements, a solenoid, one of said elements being electrically connected with the solenoid, means connecting the solenoid and the other of said 110 elements with a source of electrical supply, and an extension carried by the transfferer and engaging said bar to move said feeler elements in a direction away from the bobbin as and for the purpose specified.

2. In a loom, a bobbin having a metallic 115 wrapping thereon, replenishing mechanism including a transfferer, an insulated block, feeler mechanism comprising a pair of spaced feeler elements slideable through said block, stops carried by said elements and cooperating with said block to limit their movement in one direction, resilient elements carried by the block and engaging 120 said stops to urge and normally maintain said elements in contacting engagement with the bobbin, a solenoid, one of said elements being electrically connected with said solenoid, means connecting the solenoid and other of said elements with a source of elec- 125 130

trical supply, the corresponding outer extremities of said elements being upturned, an extension carried by the transferrer, and a bar connecting said upturned extremities and disposed to be engaged by said extension, whereby said elements are moved in a direction away from the bobbin as and for the purpose specified.

In witness whereof, I have hereunto set
10 my hand.

GEORGE W. NICELY.
